UNITED STATES PATENT OFFICE

2,173,873

SEPARABLE DRIVE FOR PRINTING PRESSES

Donald L. Boyd, Huntington, W. Va., assignor
to, Carb-O-Spot Corporation, Athens, OhioOriginal application June 28, 1938, Serial No.
216,192. Divided and this application November
30, 1938, Serial No. 243,085

3 Claims. (CL 101—351)

My invention relates to that class of presses, which is described in my copending application, Serial No. 216,192, filed June 28, 1938, of which this application is a division.

5 As set forth in that application, the wax carbon which is used in the press must be melted before it is usable and it also must be maintained at a critical temperature.

As described in that specification, the heating 10 of the parts and the ink fountain containing the wax carbon is accomplished by circulating a hot fluid through the rolls and a jacket formed on the ink fountain.

This has been found in practice to be a very 15 satisfactory method of furnishing the requisite heat. It is well known to persons skilled in the art that it is frequently necessary, on a press of this type, to stop the printing press for various purposes, which are so well understood so as not 20 to require description. If this is done, there is a very grave danger of the "shut down" burning both the rollers and the wax carbon.

It has been found in practice that if the carbon exceeds the critical temperature that although it will turn out what is apparently a perfectly satisfactory piece of work, but when one comes to use it, it will not transfer, and the job is useless.

My invention has for its object to provide apparatus whereby the printing part of the press 30 can be stopped for any desired purpose, but the ink fountain and form rollers will continue to revolve, thus entirely avoiding the above difficulty.

35 A further object is to provide for the driving means for both the printing and inking mechanisms to be synchronized so as to insure uniform operation.

A further object is to provide additional heating means extraneous from the fluid to maintain the desired temperature on the other parts of the press.

My means of accomplishing the foregoing objects may be more fully comprehended by having reference to the accompanying drawings, which are hereunto annexed and are a part of this specification in which:

Fig. 1 is a side elevation of the gear side of a press equipped with my improved separable drive, 50 with the oil pump, pipe and pipe connections left out for clarity;

Fig. 2 is a rear end view of the press, with the oil pump, pipe and pipe connections left out for clarity;

55 Fig. 3 is a fragmentary side view showing the

driving gears, oil pump, oil pump connections and ink fountain;

Fig. 4 is a top plan view of the press, showing diagrammatically the relationship of its various parts;

Fig. 5 is a fragmentary detail view showing chain tightener; and

Fig. 6 is a fragmentary detail view showing the shifting means.

Similar reference numerals refer to similar parts throughout the entire specification.

As shown in the drawings, the press is formed by a frame consisting of two side frames 1 and 2 which are adapted to carry shafts 3 and 4 upon which are mounted the impression cylinder 5 and the plate cylinder 5a. The latter cylinder is in contact with a form or distributor roller 6 which receives ink from an ink fountain roller 7 which is mounted in a partially immersed position in the ink fountain 8.

The ink fountain 8 is provided with a jacket 10 through which may be circulated fluid such as hot oil, for the purpose of supplying the heat necessary to enable the wax carbon to be worked. The form and ink fountain rollers are connected, 15 in series, by means of suitable pipe connections 11 which lead from a circulating pump 12. The oil passes through the ink fountain roller 7 and then through pipe connections 13 which lead to the distributor or form roller 6, then passes 30 through pipe connections 13a to the jacket 10 of the ink fountain 8. Thence it is returned through pipe 14 to the pump which, as shown, is driven by a motor 14a, thus insuring a continuous circulation of the heating fluid. It may 35 be desirable, in some cases, to provide a supply tank (not shown) which can be connected to the ink fountain and may be controlled by a valve.

The press is driven by belt 15 which drives a pulley 16, carried by a shaft 17, the power may 40 be furnished by a standard motor (not shown) or any other suitable driving means may be employed.

On the shaft 17, I mount a gear 18 which meshes with a gear 19, loosely mounted and 45 slidably on a shaft 20. The gear 19 is provided with a laterally extending hub 21 to which is fitted a fork 22. This fork is actuated by a rod 23 which extends to the feeder side of the press, a suitable handle 24 being provided for 50 shifting the rod 23. The gear 19 meshes with the gear 26 which rotates the impression cylinder 5. Obviously, by pulling on the handle 24, the gear 19 will be disengaged from the gear 26 and from the gear 18, and the printing mecha-

nism will stop and remain stationary until the operator again presses on the handle 24 to slide the gear 19 on the shaft 20 into mesh with the teeth of gears 18 and 26.

5 The independent drive for the ink fountain roller 7 and form roller 6 consists of a sprocket 31 mounted on the shaft 17. This sprocket 31 drives a chain 32, indicated by dotted lines, which in turn drives a sprocket 33 mounted upon a 10 shaft 34, which carries a gear 35 which meshes with a gear 36, mounted on the shaft of the form roller 6.

15 On the feeder side of this roller 6, I mount a gear 37 which in turn meshes with a gear 38 on the shaft of the ink fountain roller 7. Means for tightening the chain 32 consists of an intermediate sprocket 39 carried by an arm 40 which is arranged to swing upon the shaft 17.

20 It will be clear from the foregoing that the rotation of the form roller 6 and the ink fountain roller 7 is continuous as long as the pulley 16 is driven by the belt 15 which rotation is synchronized with the printing press when the gear 19 is in mesh, since both the sprocket 31 and the gear 18 are secured upon a common shaft.

25 My means of heating the other parts of the press are clearly seen in Fig. 1 and consists of a hood 41, which is pivotally mounted on a shaft 42 and is held in position by means of a set screw 43. When work is to be done on the press, this 30 hood can be swung to the position shown in Fig. 1 in dotted lines, thus permitting access to the parts of the press, for any desired purpose.

35 In operation, it is swung from the position shown in dotted lines to the one shown in full lines. This hood is provided with a plurality of radiant heaters 44 of strip form. In some cases the strip heaters 44 may be omitted and the hood 41 will serve to retain the heat otherwise supplied to the parts of the press.

40 The impression cylinder 5 is surrounded by a somewhat similar hood 45, one portion of which extends around and beneath the plate or printing cylinder 5a. Additional means are provided by 45 a second hood 46 which is pivoted upon a support 47 so that it can be swung into the position shown in dotted lines to permit access to the press when necessary; when the press is in operation, it is in the position shown in full lines. 50 This hood is also provided with radiant strip meters 48. In this way I am able to avoid loss of heat from the press as well as supplying additional heat when necessary to keep the working parts up to the requisite temperature.

55 As pointed out in the parent application, the fumes arising from the melted wax carbon when the press is in operation, are quite annoying as they are sickening and sweetish fumes which may prove unhealthful to the operator of the press. 60 I avoid any deleterious consequences from this cause, by providing an exhaust hood 49 which, as shown in Figs. 1 and 3, is mounted above the

ink fountain 8, suitable pipe connections being provided to connect the hood 49 to any desired air exhausting apparatus (not shown). In this way, all disagreeable results to the operator from the fumes are overcome.

Having described my invention, what I regard as new and desire to secure by Letters Patent is:

1. In a rotary press, having a printing cylinder adapted to carry plates for printing, an impression cylinder adapted to contact the printing cylinder, a form roller which contacts said printing cylinder, an ink fountain, an ink fountain roller partially immersed therein in contact with said form roller; means to drive said press and its parts comprising a driven shaft, a sprocket thereon, a gear on said shaft, a gear on the impression cylinder meshing with a gear on the printing cylinder, a sliding gear intermediate the gear on the driven shaft and the gear on the impression cylinder, manually operable means to disengage said sliding gear whereby the printing mechanism will become stationary while said driven shaft continues to revolve, a chain on said sprocket which drives a second sprocket to drive a train of gears which rotate said form and ink fountain rollers and engaging gears carried by said form and ink fountain rollers positively driving the same.

2. In a rotary press, having a printing cylinder, an impression cylinder, a form roller adapted to contact said printing cylinder, an ink fountain, an ink fountain roller in contact with said form roller; a common frame supporting said cylinders and rollers, means for driving said cylinders and said rollers comprising gearing interconnecting said form and fountain rollers, means to continuously drive the form roller and through said gearing the ink fountain roller, and means in the driving means for disconnecting the drive to the cylinders while maintaining the operation of the ink fountain roller and form roller.

3. In a rotary press, having a heated printing cylinder adapted to carry plates for printing, a heated impression cylinder adapted to contact the printing cylinder, a heated form roller which contacts said printing cylinder, a heated ink fountain, a heated ink fountain roller partially immersed therein to contact with said form roller; a common frame supporting said cylinders and rollers, driving means for said cylinders and rollers comprising means gearing said form and fountain rollers together, means to continuously drive the form roller and through said gearing the ink fountain roller, means synchronized with the drive for the form roller and ink fountain roller for driving the printing cylinder and the impression cylinder, and means in said cylinder driving means for disconnecting the drive to said cylinders while maintaining the operation of said rollers.

DONALD L. BOYD.
